CATALYTIC ESTERIFICATION OF GLUCOSIDES WITH FATTY ACIDS

John P. Gibbons, Pittsburgh, Pa., assignor to Corn Products Refining Company, New York, N. Y., a corporation of New Jersey

No Drawing. Application June 21, 1952,
Serial No. 294,936

19 Claims. (Cl. 260—210)

This invention relates to the production of esters of glycosides, and more particularly to the production of fatty acid esters of glycosides, by direct esterification of a glycoside with a fatty acid.

The classical method for the preparation of fatty acid esters of glycosides employs the reaction of a glycoside with the fatty acid halide, usually in the presence of an excess of an organic base, such as quinoline or pyridine, which combines with the hydrogen halide formed by the reaction. Upon completion of the esterification, the reaction mixture is poured into cold water, from which the ester is extracted with a water immiscible solvent. The crude ester is then obtained from the extract by distilling off the solvent.

This method is costly for commercial production of fatty acid esters of glycosides, because of the lengthy processing and numerous steps required, in addition to the fact that the fatty acid halides are considerably more expensive than the free fatty acid.

However, direct esterification of glycosides of the free fatty acids has been found to be unfeasible by the usual methods employed for the direct esterification of alcohols. These procedures utilize strongly acidic catalysts, e. g. sulfuric or hydrochloric acids, to bring about the reaction of the alcohol with the fatty acid. When it is attempted to esterify directly glycosides by such methods, extensive degradation of the glycosides occurs, as evidenced by excessive caramelization and, eventually, complete carbonization of the reaction mixture, resulting in extremely poor yields at best.

Our copending application, Serial No. 294,937, filed June 21, 1952, describes a method whereby glycosides can be directly esterified with free fatty acids, without appreciable destruction of the glycoside and with good yields of the esters, by heating a mixture of the glycoside and free fatty acid under controlled conditions without a catalyst.

It has been further discovered, however, that glycosides can also be directly esterified with free fatty acids by heating the glycoside and the free fatty acid under controlled conditions in the presence of an alkaline catalyst. The use of the alkaline catalyst presents the advantage that somewhat shorter reaction periods, which tend to minimize color formation, may be used. This is of particular importance in commercial production, where a reduction in processing time represents a reduction in cost.

It was quite surprising that alkaline catalysts could be successfully employed for the direct esterification of glycosides, inasmuch as alkaline materials are usually not good catalysts for esterification reactions.

It is an object of this invention to provide an improved method for the direct esterification of glycosides with free fatty acids. Another object of this invention is to provide a process for the production of glycoside esters of high quality, in good yields, and more economically than was possible heretofore. A further object of this

2

invention is to provide a process for direct esterification of glycosides with reduction in color formation and with shorter reaction periods. It is also an object of this invention to provide a catalytic method for esterification of glycosides. Other objects and advantages will appear hereinafter.

The present invention comprises heating the free fatty acid with a glycoside in the presence of an alkaline catalyst at temperatures within the range of about 160° C. to about 300° C. until the desired degree of esterification has been attained.

Diesters, triesters, and tetraesters may be prepared by the process of this invention by appropriate control of the reaction time, temperature and/or ratio of reactants.

Glycosides of the hexoses, pentoses, and other sugars may be employed in the present process. Advantageously they should be of high purity, containing substantially no free mineral acid and only minimum amounts of free sugar, if any, in order to avoid undesirable side reactions giving rise to extremely dark colored products.

The fatty acids suitable for use in this invention are those which contain from 6 to 20 carbon atoms in their aliphatic chains. Both saturated and unsaturated fatty acids, in the pure state or as mixtures, such as are obtained by the saponification of vegetable oils, and synthetic mixtures of fatty acids are suitable. Some examples of suitable fatty acids are caproic, lauric, palmitic, oleic, stearic, linoleic, and linolenic acids, as well as the fatty acids of dehydrated castor oil, linseed oil, corn oil and soy bean oil. Obviously, if mixtures of fatty acids are employed, mixed esters will be obtained.

The alkaline catalysts suitable for use in the present process include metal oxides and hydroxides, e. g. the alkali metal hydroxides and alkaline earth oxides, as well as alkali and alkaline earth salts of weak acids, e. g. acetic acid. Examples of suitable catalysts include litharge, barium acetate, calcium acetate, sodium hydroxide, and calcium oxide. Mixtures of such materials may also be employed.

The ratio of glycoside to free fatty acid employed in the reaction is not critical, except that the amount of free fatty acid must be, obviously, at least equivalent to that theoretically required to produce the desired degree of esterification; i. e. if a tetraester is desired, at least 4 mols of fatty acid will be necessary. Similarly, if a di- or triester is desired, at least 2 or 3 mols, respectively, of fatty acid must be employed to substantially completely convert the glycoside to the corresponding ester. However, an excess of fatty acid may be used, if desired.

When an excess of fatty acid over that theoretically required to produce the desired ester is employed in the case of di- and triesters, the degree of esterification is controlled by suitable choice of reaction conditions, such as temperature and reaction time, which are interdependent variables.

The amount of catalyst employed is not critical. However, amounts within the range of about 0.05 percent to about 0.5 percent will usually be satisfactory, although larger or smaller percentages of catalyst may be employed, if desired.

The temperature utilized to accomplish the esterification is important, since too high a temperature tends to produce undesirable side reactions, whereas too low a temperature results in extremely slow rates of esterification. Temperatures within the range of about 160° C. to about 300° C. give good yields of esters of desirable quality within a reasonable length of time, and, therefore, are preferred.

In many cases the color of the final product may be improved by maintaining the temperature at the beginning of the reaction at the lower end of the range and

increasing the temperature, preferably stepwise, as the esterification proceeds.

For example, the temperature may be maintained below 200° C. until the esterification is about 50 percent completed, then above 200° C. for the remainder, or the temperature may be maintained within the lower portion of the aforesaid range until the esterification is approximately 75 percent completed, and thereafter increased preferably to about 230° C. to about 250° C., until the esterification is completed. The latter procedure is especially suitable when preparing a tetraester. The progress of the esterification may conveniently be followed by measuring the amount of water liberated in the reaction, which will be discussed more fully hereinafter.

The reaction time depends upon the temperature employed, the particular reactants involved, the degree of esterification desired (di-, tri-, or tetraester), and also to some extent upon whether or not the water of esterification is removed as formed.

Since esterification is a reversible reaction in the presence of water, and water is one of the products formed in a direct esterification, it is advantageous to provide means for removal of the water of esterification as it is formed in order to force the esterification to substantial completion. It is also advantageous to agitate the reaction mixture during the esterification, as this tends to increase the esterification rate somewhat and also to give a more uniform heat distribution throughout the reaction mixture.

The removal of the water is facilitated, and hence the reaction rate increased, by the application of a slight vacuum to the system. The removal of water is conveniently accomplished by the addition to the reaction mixture of a substance which forms an azeotrope with water, e. g. benzene, toluene, or xylene. Such addition also accelerates the reaction rate.

Passage of an inert gas such as nitrogen or carbon dioxide, over the surface of the reaction mixture although not essential, particularly when an azeotrope is employed for removal of water, tends to improve the color of the final products.

The glucoside esters produced according to the process of this invention are particularly useful as drying oils, for example, in varnishes.

The following examples, which are intended as typical and informative only and not in a limiting sense, will further illustrate the invention:

Example 1

284.1 grams (equivalent to 1 mol) of linseed oil fatty acids (Acid No. 197.5), 48.5 grams methyl alpha-D-glucoside (equivalent to 0.25 mol) and 0.14 gram of litharge (0.05% on the weight of fatty acids) were placed in a three liter 3-necked flask equipped with a water distilling trap (Dean-Stark tube) attached to a reflux condenser, thermometer, gas inlet tube and a mechanical stirrer. While agitating in an atmosphere of carbon dioxide, the mixture was heated as rapidly as possible to 165° C. by means of a hemispherical electric mantle. At this point xylene was added through the condenser to entrain the water of esterification. The reaction was held between 200° C. and 220° C. for 2 hours, at 235° C. for 2 hours, and finally at 250° C. to 270° C. for 2 hours. After jetting off the xylene with carbon dioxide and cooling to room temperature, the yield was 311.5 grams of a red oil with an acid number of 22 (88.8% ester), a saponification number of 177.5, a Hellige color of 154 and a Gardner viscosity of 500 centipoises.

Example 2

In an apparatus similar to that described in Example 1, 1200 grams (equivalent to 4.175 mols) of linseed oil fatty acids (Acid No. 199.5), 203 grams of methyl alpha-D-glucoside (1.045 moles), 1.8 grams of barium acetate and 4.2 grams of calcium acetate was heated as rapidly as possible to 165° C. while stirring in a nitrogen atmos-

phere. At this point xylene was added to form an azeotrope with the water of reaction. The temperature was maintained between 225° C. and 235° C. for an additional 7 hours. After removing the xylene by jetting with nitrogen and cooling to room temperature, the yield was 1336 grams of a red oil with an acid number of 25.4 (87.3% ester), a saponification number of 181, a Hellige color of 16 and a Gardner viscosity at 25° C. of 125 centipoises.

Example 3

In an apparatus similar to that described in Example 1, 141 grams of linseed oil fatty acids (Acid No. 199—equivalent of 0.5 mol), 24.3 grams of methyl alpha-D-glucoside (0.125 mol), and 0.14 grams of magnesium oxide was heated rapidly to 165° C. while sparging with carbon dioxide. At this point xylene was added to remove water by azeotropic distillation. The following heating cycle was then employed: 2 hours at 195° C. to 197° C., 2 hours at 216° C. to 220° C., 2 hours at 230° C. to 231° C. and finally at 250° C. to 252° C. for an additional 2 hours. After jetting off the xylene with carbon dioxide and cooling to room temperature, the yield was 153 grams of a dark-colored oil. The product had an acid number of 18.1 (91.9% ester), a saponification value of 181, a Hellige color of 16, and a Gardner viscosity of 200 centipoises.

Example 4

In an apparatus similar to that described in Example 1, 290 grams (equivalent to 1 mol), of oleic acid (Acid No. 195), 97 grams of methyl alpha-D-glucoside (0.5 mol) and 1.25 grams of sodium hydroxide was heated as rapidly as possible to 173° C. while stirring in an atmosphere of nitrogen. At this point toluene was added for azeotropic removal of the water of esterification. The temperature was maintained between 173° C. and 194° C. for 6 hours. The reaction mass was then allowed to cool to room temperature and dissolved in a liter of equal volume of benzene and methanol. This solution was treated under reflux for 1 hour with 50 grams of activated (Nuchar W), filtered and the solvent removed from the filtrate by distillation. The yield was 361 grams of a red oil having an acid number of 12.3 (93.7% ester), a saponification number of 150.5 and a Hellige color of 15.

Example 5

In an apparatus similar to that described in Example 1, 282 grams (equivalent to 1 mol) of stearic acid (Acid No. 199), 48.5 grams of methyl alpha-D-glucoside (0.25 mol) and 0.85 gram of calcium oxide was heated rapidly to 174° C. while agitating and sparging with carbon dioxide. Xylene was then added to entrain the water of esterification. The reaction was held between 180° C. and 200° C. for 2.8 hours, and then between 230° C. and 250° C. for an additional 9.5 hours. After jetting off the xylene with carbon dioxide and cooling to room temperature, 311 grams of a dark brown waxy solid was obtained which had an acid number of 17.8 (91.1% ester) and a saponification number of 178.5.

Example 6

In an apparatus similar to that described in Example 1, 402 grams (equivalent to 2 mols) of lauric acid (Acid No. 279), 97 grams of methyl alpha-D-glucoside (equivalent to 0.5 mol) and 0.4 gram of calcium oxide was heated rapidly with agitation and carbon dioxide sparging to 165° C. Xylene was then added to azeotropically remove water of esterification. The reaction temperature was held between 177° C. and 180° C. for 3 hours, between 190° C. and 200° C. for 2.5 hours, at 215° C. for 1 hour, then at 230° C. for 1.7 hours, and finally between 245° C. and 248° C. for 4 hours. After jetting off the xylene and unreacted lauric acid at 248° C. with carbon dioxide, the product was cooled to room temperature, dissolved in 1000 ml. of benzene and decolorized by refluxing for 1 hour with 50 grams of activated carbon

5.

(Nuchar W). The carbon was filtered off and the benzene removed from the filtrate by distilling in vacuo. The yield was 381 grams of a light tan oil with an acid number of 14.7 (94.7% ester), a saponification number of 234 and a Hellige color of 8.

Example 7

In an apparatus similar to that described in Example 1, 211.5 grams (equivalent to 0.75 mol) of stearic acid (Acid No. 199), 48.5 grams of methyl alpha-D-glucoside (equivalent to 0.25 mol), 0.64 gram of calcium oxide and 13 grams of activated carbon (Nuchar W) was heated rapidly to 165° C. while stirring in an atmosphere of carbon dioxide. Xylene was added to remove the water of esterification by entrainment. The temperature was maintained between 185° C. and 205° C. for 6 hours. After jetting off the xylene and cooling to room temperature the product was dissolved in benzene and the carbon filtered off. To the filtrate was added 13 grams of activated carbon and the resulting solution refluxed for 1 hour. After removing the carbon by filtration and stripping off the benzene, 216 grams of a light tan, wax-like solid was obtained; which had a melting point of 50-54° C., an acid number of 21.7 (89.1% ester), and a saponification number of 171.5.

One hundred grams of this ester was dissolved in a liter of ether under reflux, and the solution was washed with six 50 mL portions of 2 percent aqueous sodium carbonate in a separatory funnel. Following removal of the sodium carbonate by washing with water and the ether by distillation, 75.1 grams of a light brown wax was recovered which had a melting point of 52-54° C., and acid number of 1.2 (99.4% ester), and a saponification value of 171.

Example 8

In an apparatus similar to that described in Example 1, 139.9 grams (equivalent to 0.5 mol) of linseed oil fatty acids (Acid No. 200.5), 27.5 grams (equivalent to 0.125 mol) of allyl alpha-D-glucoside (85%-90%, M. P. 85-90° C., reducing sugar 0.35%) and 0.14 gram of calcium oxide was heated rapidly to 194° C. while agitating and sparging with carbon dioxide. Xylene was added to entrain the water of esterification and the temperature maintained between 194° C. and 204° C. for 6.75 hours. The xylene was then removed by bubbling through the reaction mixture a rapid stream of carbon dioxide. On cooling to room temperature, the yield was 162 grams of a dark red oil with an acid number of 56.6 (71.8% ester), a saponification number of 175, a Hellige color of 18+ and a Gardner viscosity of 85 centipoises.

Example 9

In an apparatus similar to that described in Example 1, 76.9 grams (equivalent to 0.2745 mol) of linseed oil fatty acids (Acid No. 200.5), 15 grams (equivalent to 0.915 mol) of methyl beta-D-arabinoside (2.8% reducing sugar, M. P. 158°-163° C.) and 0.08 gram of calcium oxide was heated rapidly to 156° C. while stirring in a carbon dioxide atmosphere. Xylene was added at this point to azeotropically remove the water of reaction. The temperature was maintained between 160° C. and 190° C. for 6 hours; then the xylene was jetted off with carbon dioxide. After cooling to room temperature, the yield was 89.9 grams of a dark red oil with an acid number of 90.2 (55% ester), a saponification number of 179, a Hellige color of 18+ and a Gardner viscosity at 25° C. of 60 centipoises.

Example 10

In an apparatus similar to that described in Example 1, 139.9 grams (equivalent to 0.5 mol) of linseed oil fatty acids (Acid No. 200.5), 24.3 grams (equivalent to 0.125 mol) of methyl alpha-D-galactoside (M. P. 90-98° C., reducing sugar 1.6%) and 0.14 gram of calcium oxide

6.

was heated rapidly with agitation and carbon dioxide sparging at 150° C. At this point xylene was added as a water azeotropic agent. The temperature was held between 160° C. and 193° C. for 6 hours, then the xylene was jetted off with carbon dioxide and the reaction product cooled to room temperature. The yield was 156 grams of a dark red oil with an acid number of 64.3 (68% ester), a saponification number of 185.5, a Hellige color of 18+ and a Gardner viscosity at 25° C. of 100 centipoises.

Example 11

The effect of a catalyst on the reduction of acid number in the esterification of 1 mol of methyl alpha-D-glucoside with 4 mols of linseed oil fatty acids at 200° C. and 230° C. in a carbon dioxide atmosphere is illustrated in the following table:

Reaction Time (hr.)	Acid Number of Reaction Mixture			
	at 200° C.		at 230° C.	
	No. Catalyst	.0063 mol of PbO per mol of Fatty Acids	No. Catalyst	.0063 mol of PbO per mol of Fatty Acids
1		94	86	78
2		81	64	59
3		72	52	52
4		66	43	46
5		61	37	41
6		57	32	38
7		52	28	15
8		50	26	35
9		48	23	13
10		46	21	31

Example 12

In an apparatus similar to that described in Example 1, 1124 grams (equivalent to 4 mols) of linseed oil fatty acids (Acid No. 199), 203.7 grams of methyl alpha-D-glucoside (1.05 mol), and 5.62 grams of litharge (.0252 mol) was heated rapidly to 165° C. while stirring and sparging with carbon dioxide. Xylene was added to entrain the water of esterification. The reaction was held at 186°-188° C. for 1.8 hours, then at 215° C. for 1.5 hours and finally at 230°-235° C. for 4 hours. After jetting off the xylene with carbon dioxide and cooling to room temperature, 1260 grams of a brownish oil was obtained which had an acid number of 4.2, a saponification number of 176, a Hellige color of 13 and a viscosity of 165 centipoises.

I claim:

1. A process for the production of fatty acid esters of glycosides by the direct esterification of glycosides with free fatty acids, comprising heating a mixture of a glycoside, from the group consisting of methyl glycoside and allyl glycoside, and free fatty acid containing about 6 to about 22 carbon atoms in the aliphatic chain in the presence of an alkaline catalyst at a temperature within the range of about 160° C. to about 300° C. until the desired degree of esterification has been attained, said catalyst being from the group consisting of alkali metal hydroxides, alkaline earth oxides, alkali salts of weak acids, and alkaline earth salts of weak acids.
2. Process according to claim 1 wherein said catalyst is present in an amount within the range of about 0.05 per cent to 0.5 per cent, based on the weight of the fatty acids.
3. Process according to claim 1, wherein said free fatty acid is a mixture of fatty acids obtained by saponification of a vegetable oil.
4. Process according to claim 1, wherein said mixture of free fatty acids is linseed oil fatty acids.
5. Process according to claim 1, wherein said mixture of fatty acids is dehydrated castor oil fatty acid.

6. Process according to claim 1, wherein said mixture of fatty acids is soy bean oil fatty acids.

7. Process according to claim 1, wherein said fatty acid is stearic acid.

8. Process according to claim 1, wherein said alkaline catalyst is litharge.

9. Process according to claim 1, wherein the water of esterification is removed from the reaction mixture during esterification.

10. Process according to claim 1, wherein the temperature is gradually increased during the esterification.

11. Process according to claim 1, wherein the temperature is increased stepwise during the esterification.

12. Process according to claim 1, wherein the water of esterification is removed by azeotropic distillation.

13. Process for the production of a linseed oil fatty acid tetraester of methyl glucoside, comprising heating a mixture of methyl glucoside, linseed oil fatty acids, xylene, and litharge at a temperature increased stepwise within the range of about 165° C. to 270° C. for 6 hours, under an atmosphere of carbon dioxide; the water of esterification being continuously removed by azeotropic distillation with xylene; the molar ratio of linseed oil fatty acids to methyl glucoside being at least 4:1, said litharge being present in an amount of about 0.05 percent, based on the weight of the linseed oil fatty acids.

14. Process for the production of linseed oil fatty acids tetraester of methyl glucoside, comprising heating a mixture of linseed oil fatty acids, methyl glucoside, xylene, and an alkaline earth acetate, at a temperature within the range of about 225° C. to about 235° C. for 7 hours, under an atmosphere of nitrogen; the water of esterification being continuously removed by azeotropic distillation with xylene; the molar ratio of linseed oil fatty acids to methyl glucoside being at least 4:1, said alkaline earth acetate being present in an amount of about 0.5 percent, based on the weight of the linseed oil fatty acid.

15. Process for the production of the stearic acid tetraester of methyl glucoside, stearic acid, xylene, and calcium oxide at a temperature increased stepwise within the range of about 180° C. to about 250° C. for about 12 hours, under an atmosphere of carbon dioxide; the molar ratio of stearic acid to methyl glucoside being at least 4:1, the water of esterification being continuously removed by azeotropic distillation with the xylene, said calcium oxide being present in an amount of about 0.3 percent, based on the weight of the stearic acid.

16. Process for the production of the stearic acid triester of methyl glucoside, comprising heating a mixture of stearic acid, methyl glucoside, xylene, and calcium oxide at a temperature within the range of about 185° C. to about 205° C. for about 6 hours, under an atmosphere of carbon dioxide; the water of esterification being continuously removed by azeotropic distillation with the xylene; the molar ratio of stearic acid to methyl glucoside being at least 3:1, said calcium oxide being present in

an amount of about 0.3 percent, based on the weight of the stearic acid.

17. Process for the production of the linseed oil fatty acids triester of allyl glucoside comprising heating a mixture of linseed oil fatty acids, allyl glucoside, xylene and of calcium oxide, at a temperature within the range of about 194° C. to about 204° C. for about 7 hours; the water of esterification being continuously removed by azeotropic distillation with the xylene; the molar ratio of linseed oil fatty acids to allyl glucoside being about 4:1, said calcium oxide being present in an amount of about 0.1 percent, based on the weight of the linseed oil fatty acids.

18. Process for the production of linseed oil fatty acids diester of methyl arabinoside comprising heating a mixture of linseed oil fatty acids, methyl arabinoside, xylene, and of calcium oxide, at a temperature within the range of about 156° C. to about 190° C. for about 6 hours, under an atmosphere of carbon dioxide; the water of esterification being continuously removed by azeotropic distillation with the xylene; the molar ratio of linseed oil fatty acids to methyl arabinoside being about 3:1, said calcium oxide being present in an amount of about 0.1 percent, based on the weight of the linseed oil fatty acids.

19. Process for the production of linseed oil fatty acids, triester of methyl galactoside, comprising heating a mixture of linseed oil fatty acids, methyl galactoside, xylene and calcium oxide at a temperature within the range of about 160° C. to about 193° C. for about 6 hours, under an atmosphere of carbon dioxide; the water of esterification being continuously removed by azeotropic distillation with the xylene; the molar ratio of linseed oil fatty acids to methyl galactoside being about 4:1, said calcium oxide being present in an amount of about 0.1 percent, based on the weight of the linseed oil fatty acids.
